HARNESS FOR CROSS WEAVING

John Jacob Kaufmann, Elkins Park, Pa., assignor
to Steel Heddle Manufacturing Company, Phil-
adelphia, Pa., a corporation of Pennsylvania

Application January 9, 1933, Serial No. 650,880

9 Claims. (Cl. 139—52)

My invention relates to metallic loom harness for use in that method of weaving known as "cross weaving", sometimes called "doup weaving" or "leno weaving", in which the warp threads are crossed or twisted about each other at as many points in the shed as may be desirable, either for a succession of picks, or according to a pattern or design to be produced.

This invention relates more particularly to the construction and formation of the guide or lifting heddles which are employed to raise the doup needles and thus cause each of the doup warps controlled thereby to be disposed on one side or the other of its ground warp as required.

15 The principal object of my invention is to provide a metal harness for cross weaving in which possibility of fouling of the warp threads will be eliminated, which will be simple, durable, and efficient for various types of cross weaving, and which 20 will be relatively inexpensive in construction.

25 With the foregoing object in view, my invention contemplates the provision of a doup needle, preferably punched from sheet metal, and a pair of lifting heddles of novel conformation for each doup needle, each of which heddle is made from a single strip of thin flat metal.

30 My present invention insures the utmost freedom in the shedding of the warp, as well as serving to guide the warp during the shedding action so that the same will not be caught on the top of the doup needle or jammed between the needles and the lifting heddles and thus improperly raised.

35 The nature and characteristic features of my present invention will be more readily understood from the following description, taken in connection with the accompanying drawing forming part hereof, in which:

40 Figure 1 is an elevational view of one pair of heddles, and the associated parts, for controlling a pair of warp ends;

Fig. 2 is an enlarged detail view of the central portion thereof;

45 Fig. 3 is a side elevation of that portion of the structure shown in Fig. 2; and

Fig. 4 is a face view of a preferred form of doup needle employed in association with the lifting heddles for controlling the doup warp.

50 It will of course be understood that the description and drawing herein contained are illustrative merely, and that various changes and modifications may be made in the structure disclosed without departing from the spirit of the invention.

55 Referring to the drawing, in the particular embodiment of my invention therein shown, 10 is the doup needle, which is preferably made by punching or stamping from a thin flat strip or sheet of metal. The doup needle 10 has at one 60 end an eye portion 11, in which the eye 12 for

the control of the doup warp 13 is located. The ground warp 14 extends freely between the pair of lifting heddles, and is controlled, in the event that it is desired to raise and lower the same, by separate harness (not shown). The outer margin 15 of the eye end 11 of the doup needle 10 is arched or curved, and the inner under margins 16 thereof are also curved, in gothic formation, meeting in a central apex.

Extending from the eye end 11 of the doup 10 needle 10 are two legs 17, which terminate in enlarged portions 18, each of which is provided with a slot 19, for connection of the doup needle 10 with the needle lowering means, such for example as the bars or rods 20 which extend through the slots 19.

There are provided two lifting heddles 21, each of which is formed from a single strip of thin flat metal. The upper portion 22 and the lower portion 23 of each of the lifting heddles are each 20 preferably disposed in a plane parallel to the plane of the doup needle 10, and also parallel to the general longitudinal extension of the warp ends 13 and 14 controlled by the harness.

The central part of each lifting heddle 21 comprises an upper straight portion 24, an intermediate inclined offset portion 25, and a lower straight portion 26, all disposed in planes at right angles to the planes of the upper and lower portions of the heddle proper, this arrangement being secured by imparting a quarter twist to the strip from which the heddle is formed, at the points 27 and 28.

The central part of the heddle 21 is slotted, as at 29, this slot extending entirely through the inclined offset portion 25 of the central part of the heddle, and also extending upwardly a short distance into the portion 24, and downwardly a short distance into the portion 26.

Near the upper and lower extremities of each 40 of the heddles 21 there are provided slots or mortises 30, for mounting the lifting heddles 21 on the harness frame rods or bars 31.

The twisting of the central portions of the heddle out of the plane of the upper and lower portions thereof provides a guard or guide which extends over the eye end 11 of the doup needle and prevents the ground warp 14 from being caught on the horizontal portion of the curved margin 15 of the eye end 11 of the doup needle 10. The 50 guard which is thus provided will also serve to prevent the warp ends which pass between adjacent sets of heddles from becoming lodged or caught on the eye end of the doup needle.

By the provision of the slotted offset portion 55 25 of the lifting heddle, an appreciable space 32 will be secured between the side margin of the leg portion 17 of the doup needle 10 and the upper portions 22 and 24 of the lifting heddle which remains in the lowered position, thus preventing 60

the ground warp 14 from being gripped between the doup needle 10 and the upper portions 22 and 24 of one of the lifting heddles when the other is raised, which would improperly raise the ground warp and cause a mispick.

5 By reason of the githic formation of the inner margins 16 of the eye end 11 of the doup needle 10, said eye end will be properly centered with respect to the lifting heddle, and in this manner 10 the portions 24, 25 and 26 of the heddle will be so positioned with respect to the eye end 11 of the doup needle 10, as the lifting heddle is raised, as to guide any of the warp ends which would tend 15 to lodge on the top of the needle to such position that the same will readily slide down the side of the needle.

Furthermore, cross weaving harness constructed as aforesaid will be free in its action, thus 20 greatly easing the shedding motion as the lifting 25 heddles are respectively raised and lowered.

I claim:

1. In harness for cross weaving, a lifting heddle made of a single flat strip of metal, the central part of the heddle comprising an upper straight portion, an intermediate offset portion, and a lower straight portion, the central part being twisted with respect to the upper and lower parts whereby the several portions thereof are disposed in planes each at an angle to the general 25 longitudinal extension of the warp ends thereby to provide a guard to guide the warp over the top of the doup needle, and the central part of the heddle being slotted for the extension of the doup needle therethrough.

35. 2. In harness for cross weaving, a lifting heddle made of a single flat strip of metal having its upper and lower portions each disposed in a plane parallel to the general longitudinal extension of the warp ends, the central part of the heddle being twisted with respect to the upper and lower parts and comprising an upper straight portion, an intermediate offset portion, and a lower straight portion, and the central part of the heddle being slotted for the extension of the doup 40 needle therethrough.

50. 3. In harness for cross weaving, a lifting heddle made of a single flat strip of metal having its upper and lower portions each disposed in a plane parallel to the general longitudinal extension of the warp ends, the central part of the heddle being slotted for the extension of the doup needle therethrough and being twisted with 55 respect to the planes of the upper and lower portions of the heddle and the slot in the central part being positioned so that the lower end thereof will engage and lift the needle when the heddle is raised.

4. In harness for cross weaving, a lifting heddle made of a single flat strip of metal having its upper and lower portions each disposed in a plane parallel to the general longitudinal extension of the warp ends, the central part of the heddle comprising an upper straight portion, an intermediate offset portion, and a lower straight portion, all disposed in planes at right angles to the planes of the upper and lower portions of the heddle proper thereby to provide a guard to guide the warp over the top of the doup needle, the central part of the heddle being slotted for the extension of the doup needle therethrough.

70. 5. In harness for cross weaving, a doup needle having an eye through which the doup warp extends, said needle being made of thin flat metal, a pair of lifting heddles each made of a single

flat strip of metal, the central part of the heddle comprising an upper straight portion, an intermediate offset portion, and a lower straight portion, the central part being twisted with respect to the upper and lower parts whereby the several portions thereof are disposed in planes each at an angle to the general longitudinal extension of the warp ends thereby to provide a guard to guide the warp over the top of the doup needle, and the central part of the heddle being slotted for the extension of the doup needle therethrough.

5 6. In harness for cross weaving, a doup needle having an eye through which the doup warp extends, said needle being made of thin flat metal, a pair of lifting heddles each made of a single flat strip of metal having its upper and lower portions each disposed in a plane parallel to the general longitudinal extension of the warp ends, the central part of the heddle being twisted with respect to the upper and lower parts and comprising an upper straight portion, an intermediate offset portion, and a lower straight portion, and the central part of the heddle being slotted for the extension of the doup needle therethrough.

10 7. In harness for cross weaving, a doup needle having an eye through which the doup warp extends, said needle being made of thin flat metal, a pair of lifting heddles each made of a single flat strip of metal having its upper and lower portions each disposed in a plane parallel to the general longitudinal extension of the warp ends, the central part of the heddle being slotted for the extension of the doup needle therethrough and being twisted with respect to the planes of the 15 upper and lower portions of the heddle.

20 8. In harness for cross weaving, a doup needle having an eye through which the doup warp extends, said needle being made of thin flat metal, a pair of lifting heddles each made of a single flat strip of metal having its upper and lower portions each disposed in a plane parallel to the general longitudinal extension of the warp ends, the central part of the heddle comprising an upper straight portion, an intermediate offset portion, and a lower straight portion, all disposed in planes at right angles to the planes of the upper and lower portions of the heddle proper thereby to provide a guard to guide the warp over the top of the doup needle, and the central part of the heddle being slotted for the extension of the doup needle therethrough.

25 9. In harness for cross weaving, a doup needle having an eye through which the doup warp extends, said needle being made of thin flat metal, a pair of lifting heddles each made of a single flat strip of metal having its upper and lower portions each disposed in a plane parallel to the general longitudinal extension of the warp ends, the central part of the heddle comprising an upper straight portion, an intermediate offset portion, and a lower straight portion, all disposed in planes at right angles to the planes of the upper and lower portions of the heddle proper thereby to provide a guard to guide the warp over the top of the doup needle, the central part of the heddle being slotted for the extension of the doup needle therethrough, and the inner margins of the eye portion of the needle being curved and extending to a central apex thereby to center the eye portion of the heddle with respect to the lifting heddle when the same is raised.

30 10. 6. In harness for cross weaving, a doup needle having an eye through which the doup warp extends, said needle being made of thin flat metal, a pair of lifting heddles each made of a single flat strip of metal having its upper and lower portions each disposed in a plane parallel to the general longitudinal extension of the warp ends, the central part of the heddle comprising an upper straight portion, an intermediate offset portion, and a lower straight portion, all disposed in planes at right angles to the planes of the upper and lower portions of the heddle proper thereby to provide a guard to guide the warp over the top of the doup needle, the central part of the heddle being slotted for the extension of the doup needle therethrough, and the inner margins of the eye portion of the needle being curved and extending to a central apex thereby to center the eye portion of the heddle with respect to the lifting heddle when the same is raised.
